(57) **CLAIM**

The ornamental design for a foot for a medical mobility device, as shown and described.

DESCRIPTION

FIG. 1 is a top, side perspective view of a foot for a medical mobility device showing the new design.

FIG. 2 is a side elevation view of the foot for a medical mobility device of FIG. 1.

FIG. 3 is a top plan view of the foot for a medical mobility device of FIG. 1; and,

FIG. 4 is a bottom plan view of the foot for a medical mobility device of FIG. 1 with the unclaimed environmental structure removed.

The dashed lines in the drawings illustrate environmental subject matter and form no part of the claimed design. The dash-dot-dash lines illustrate unclaimed boundary lines and form no part of the claimed design.

1 Claim, 4 Drawing Sheets
